STROBE LIGHT

Robert A. Kauffman, Reynoldsburg, Ohio, assignor to In-Flight Devices Corporation, a corporation of Ohio

Filed Nov. 27, 1967, Ser. No. 9,556

Term of patent 14 years

Int. Cl. D29—99; D26—04

U.S. Cl. D72—1

FIG. 1

FIG. 2

FIG. 3

FIG. 4

FIGURE 1 is a perspective view of a strobe light embodying my new design, the opposite side being the same in appearance.

FIGURE 2 is a side view of the design of FIGURE 1.

FIGURE 3 is a top view of the design of FIGURE 1.

FIGURE 4 is a bottom view of the design of FIGURE 1.

I claim:

The ornamental design for a strobe light, as shown and described.
